UNITED STATES PATENT OFFICE

HARRY A. INMAN, OF NEWARK, NEW YORK

CONTAINER

Application filed August 22, 1930. Serial No. 476,988.

This invention relates to a container, and especially to one intended for use in connection with fragile articles, such as eggs.

An object of the invention is to provide a generally improved and more satisfactory cushioning means in such a container to reduce breakage of eggs or other fragile articles placed therein.

Another object is the provision of satisfactory collapsible cushioning means in a container of the collapsible type, which cushioning means is so designed and constructed that it will be opened to proper position easily and automatically when the container is expanded to normal position.

A further object is the provision in a collapsible container of article supporting means which will not interfere with the collapsing of the container and which will invariably be properly positioned by the mere act of expanding the container.

To these and other ends the invention resides in certain improvements and combinations of parts, all as will be hereinafter more fully described, the novel features being pointed out in the claims at the end of the specification.

In the drawings:

Fig. 1 is a plan of a container constructed in accordance with a preferred embodiment of the invention showing the cover thrown back to open position and partially broken away;

Fig. 2 is a side elevation of the filler or partition structure of the container;

Fig. 3 is a transverse vertical section through the container;

Fig. 4 is an enlarged detailed view of a portion of Fig. 3;

Fig. 5 is an end view of the filler or partition structure partially collapsed, and

Fig. 6 is a side elevation of the filler or partition structure collapsed.

Similar reference numerals throughout the several views indicate the same parts.

This application is an improvement upon the structure disclosed in my copending application for container for fragile articles, filed April 17, 1930, Serial No. 444,910.

The container comprises a box body which

is preferably collapsible, having a bottom 11, a front wall 12, a rear wall 13, a cover 14, and a cover flap 15 arranged to extend downwardly adjacent the front wall 12 when the cover is closed, as shown in Fig. 3. Within this body there is removably placed a filler or partition structure which subdivides the body into a plurality of separate compartments, although at times this filler or partition structure may be used by itself as a container, without being placed within the body.

The filler comprises longitudinal partitions 21, 22, and 23, and a plurality of transverse partition members 25 which extend crosswise of the partitions 21, 22, and 23 when the latter are in normal expanded position, as shown in Fig. 1, but which swing to a position approximately parallel to the longitudinal partitions when the structure is collapsed by moving the partitions 21, 22, and 23 longitudinally relative to each other and inwardly toward each other. The transverse partition members 25 are provided with suitable slots interlocking with suitable slots in the partitions 21, 22, and 23 in known manner.

Article supporting means is provided in connection with the filler to support the eggs or other fragile articles in a position somewhat above the bottom 11 of the box body, so that a somewhat resilient or cushioning support is furnished in order to reduce the possibility of breakage of the articles. This cushioning means in its preferred embodiment comprises a generally V-shaped member between the partitions 21 and 22, and another generally V-shaped member between the partitions 22 and 23, as best shown in Fig. 3.

Preferably both V-shaped members together with certain supporting or affixing flanges are made of a single integral piece of cardboard or the like, suitably scored. For instance, referring to Fig. 3, each V-shaped member comprises a sloping portion 30 and another sloping portion 31 hinged to each other by means of a score line at the point 32, which point preferably rests upon the bottom 11 of the body when the container is expanded and when articles, such as eggs 33, are packed therein.

Each V-shaped article supporting member

also comprises an affixing flange 34 hingedly connected to the portion 30 by a suitable score line. The affixing flange 34 of each article supporting member is secured by any suitable means such as adhesive to one of the partitions 21, 22, or 23 near the lower edge thereof. Preferably, as shown in Fig. 3, the affixing flanges 34 of both article supporting members are secured to the middle partition 22, and when this is done, both of the article supporting members may be conveniently constructed of a single integral piece of cardboard, the flanges 34 being joined to each other by a portion 35 which bends around the bottom of the middle partition 22.

Each of the article supporting members is also provided with a flange 36 joined to the edge of the portion 31 by a suitable score line, which flange preferably extends substantially vertically downwardly and rests upon the bottom 11 so as to form a support for the outer edge of the article supporting member. Preferably also this flange 36 is folded or doubled back upon itself at 37 and thence extends upwardly as at 38 and has its upper edge somewhat above the portion 31, as shown most clearly in Figs. 3 and 4. The portions 36 and 38 are connected to each other by adhesive. This flange 36, 38 lies substantially flat against one of the partitions, such as 21 or 23, and in confined between such partition and a bearing surface 40 formed on some or preferably all of the transverse partition members 25.

When the filler or partition structure (when removed from the box body) is collapsed, the article supporting members fold up between the partitions 21, 22, and 23, as indicated in Fig. 5. When the filler is expanded, the article supporting members likewise expand to the position illustrated in Fig. 3. Such expansion is greatly facilitated by the bearing surfaces 40 of the transverse partition members cooperating with the flanges 38 of the article supporting members. The bearing surfaces 40 tend to hold each flange substantially against the adjacent partition and thus positively insure proper expansion of the V-shaped supporting member. Such expansion is also aided to some extent by the V-shaped downwardly extending lugs 41 on the transverse partition members 25, which extend into the space between the portions 30 and 31 of the supporting members and tend to expand these portions when the filler is expanded.

It will be remembered that when collapsing or expanding the filler or partition structure, the partitions 21, 22, and 23 move longitudinally relative to each other as well as transversely toward or away from each other. For this reason, the article supporting member cannot be attached rigidly to two partitions because such attachment would prevent the longitudinal movement of the partitions.

Hence each supporting member is attached rigidly only to one partition (preferably the partition 22) and may slide longitudinally relative to the other partition with which it cooperates (21 or 23). In order to prevent any possible downward sagging of the outer or unattached edge of the supporting member which is adjacent the partition 21 or 23, means is provided for supporting the article supporting member adjacent such partition 21 or 23.

In the preferred form of the invention, such supporting means comprises a slot 45 in the flange 38 of each article supporting member, and a lug engaging this slot to support the flange and thus to prevent the flange from dropping downwardly while at the same time permitting it to move longitudinally relative to the adjacent partition when the partitions are collapsed or expanded. This lug is preferably formed on one of the transverse partitions 25, and is indicated by the numeral 46 in Figs. 3 and 4. In the present instance, as shown in Figs. 2 and 6, the lugs 46 are provided on two partition members 25 and the slots 45 are made of corresponding length to cooperate with these two lugs. It is obvious, however, that a greater or less number of partition members 25 may be provided with lugs, and in actual use it has often been found satisfactory to provide only one supporting lug 46 on each side of the filler. When the partitions are being expanded or collapsed, the upper edge of the slot 45 rides along the upper surface of the lug 46 and thus holds the flange 38 at the desired predetermined elevation, preventing it and other parts of the article supporting member from dropping downwardly.

To insure proper engagement of the lug 46 in the slot 45, the lug is preferably made of such length that it extends somewhat beyond the flange 38, and the partitions 21 and 23 are accordingly provided with openings 47 opposite the lugs 46, so that the lugs may extend into these openings without interference, as shown especially in Fig. 4.

In operation, the containers are preferably shipped from the factory to the user in knocked-down form, the container bodies being collapsed and the fillers being removed from the bodies and likewise collapsed. When the user desires to utilize a container, he opens up or expands one of the box bodies, then expands one of the fillers and places the filler in the body. During the expansion of the filler, the surfaces 40 on the transverse partitions cooperate with the flanges 38 to carry these flanges outwardly away from the center partition 22 as the outer portions 21 and 23 move outwardly, thus insuring proper expansion of the V-shaped articles supporting member. At the same time the lug 46 engaging the slot 45 holds the flange 38 up in proper position and prevents them

from sagging downwardly or otherwise becoming displaced. Thus the mere act of expanding the partitions 21, 22, and 23 automatically and invariably expands the article 5 supporting members 30 and 31 and insures proper positioning thereof without any care or attention by the operator.

When the expanded filler has been placed in the body, fragile articles such as eggs 33 10 may be packed in the filler and the portions 30 and 31 of the article supporting members will act as somewhat resilient supports for the articles, so that they may be dropped into the container without great care and yet 15 will not be cracked as might occur if they came directly into contact with the flat bottom 11, and so that they will not break during shipment. Under some circumstances the partition structure itself may be satisfactorily used as a container without enclosing it 20 in a covering body.

While one embodiment of the invention has been disclosed, it is to be understood that the inventive idea may be carried out in 25 a number of ways. This application is therefore not to be limited to the precise details described, but is intended to cover all variations and modifications thereof falling within the spirit of the invention or the scope 30 of the appended claims.

I claim:

1. A container comprising a plurality of partitions movable longitudinally relative to each other from an expanded position spaced 35 from each other to a collapsed position adjacent each other, an article supporting member connected to one partition and extending in a general direction toward a second partition, and means for supporting said member 40 adjacent said second partition while permitting said member to move longitudinally relative to said second partition when the partitions are collapsed or expanded.

2. A container comprising a plurality of 45 partitions movable longitudinally relative to each other from an expanded position spaced from each other to a collapsed position adjacent each other, a foldable article supporting member connected to one partition and extending in a general direction toward a second partition and foldable between said partitions when they are collapsed, and means 50 for supporting said member adjacent said second partition while permitting said member to move longitudinally relative to said second partition when the partitions are collapsed or expanded.

3. A container comprising a plurality of 55 partitions movable longitudinally relative to each other from an expanded position spaced from each other to a collapsed position adjacent each other, an article supporting member connected to one partition and extending in a general direction toward a second partition, said supporting member including a

surface adjacent said second partition and a slot in said surface, and means including a lug engaging said slot for supporting said article supporting member adjacent said second partition while permitting said member to move longitudinally relative to said second partition when the partitions are collapsed or expanded.

4. A container comprising a plurality of partitions movable longitudinally relative to each other from an expanded position spaced 70 from each other to a collapsed position adjacent each other, a generally V-shaped article supporting member connected to one partition and extending in a general direction toward a second partition and arranged to fold up between said partitions when they are collapsed, and means for supporting said member adjacent said second partition while permitting said member to move longitudinally relative to said second partition when the partitions are collapsed or expanded.

5. A container comprising a plurality of partitions movable longitudinally relative to each other from an expanded position spaced 75 from each other to a collapsed position adjacent each other, a generally V-shaped article supporting member connected to one partition and extending in a general direction toward a second partition and arranged to fold up between said partitions when they are collapsed, said supporting member including a surface adjacent said second partition and a slot in said surface, and means including a lug engaging said slot for supporting said article supporting member adjacent said second partition while permitting said member to move longitudinally relative to said second partition when the partitions are collapsed or expanded.

6. A container comprising a plurality of partitions movable relative to each other from an expanded position spaced from each other to a collapsed position adjacent each other, a partition member extending in a generally transverse direction relative to said partitions when the latter are in expanded position, an article supporting member connected to one partition and extending in a general direction toward a second partition, and means including a slot in said supporting member and a lug on said partition member engaging said slot for supporting said article supporting member adjacent said second partition.

7. A container comprising a plurality of partitions movable longitudinally relative to each other from an expanded position spaced from each other to a collapsed position adjacent each other, a partition member extending in a generally transverse direction relative to said partitions when the latter are in expanded position, a generally V-shaped article supporting member connected to one partition and extending in a general direction toward a second partition, said supporting member including a

- tion toward a second partition and arranged to fold up between said partitions when they are collapsed, said supporting member including a surface adjacent said second partition and a slot in said surface, and means including a lug on said partition member engaging said slot for supporting said article supporting member adjacent said second partition while permitting said supporting member to move longitudinally relative to said second partition when the partitions are collapsed or expanded. 75
8. A container comprising a plurality of partitions movable longitudinally relative to each other from an expanded position spaced from each other to a collapsed position adjacent each other, a partition member extending in a generally transverse direction relative to said partitions when the latter are in expanded position, a generally V-shaped article supporting member connected to one partition and extending in a general direction toward a second partition and arranged to fold up between said partitions when they are collapsed, said supporting member including a flange lying substantially flat against said second partition and a bearing surface on said transverse partition member tending to hold said flange substantially against said second partition. 80
9. A container comprising a plurality of partitions movable longitudinally relative to each other from an expanded position spaced from each other to a collapsed position adjacent each other, a partition member extending in a generally transverse direction relative to said partitions when the latter are in expanded position, a generally V-shaped article supporting member connected to one partition and extending in a general direction toward a second partition and arranged to fold up between said partitions when they are collapsed, said supporting member including a flange lying substantially flat against said second partition and a slot in said flange, and a lug on said partition member engaging said slot for supporting said flange while permitting said flange to move longitudinally relative to said second partition when the partitions are collapsed or expanded. 85
10. A container comprising a body, a plurality of partitions placeable in and removable from said body, said partitions when removed from said body being longitudinally movable relative to each other from an expanded position spaced from each other to a collapsed position adjacent each other, a cushioning article supporting member connected to one partition and extending in a general direction toward another partition and arranged when said partitions are in said body to support an article above the bottom of said body, and means for supporting said member adjacent said second partition 90
11. A partition member for a partition comprising a generally V-shaped article supporting member connected to one partition and extending in a general direction toward a second partition and arranged to fold up between said partitions when they are collapsed, said supporting member including a flange lying substantially flat against said second partition and a bearing surface on said transverse partition member tending to hold said flange substantially against said second partition. 95
12. A partition member for a partition comprising a generally V-shaped article supporting member connected to one partition and extending in a general direction toward a second partition and arranged to fold up between said partitions when they are collapsed, said supporting member including a flange lying substantially flat against said second partition and a slot in said flange, and a lug on said partition member engaging said slot for supporting said flange while permitting said flange to move longitudinally relative to said second partition when the partitions are collapsed or expanded. 100
13. A partition member for a partition comprising a generally V-shaped article supporting member connected to one partition and extending in a general direction toward a second partition and arranged to fold up between said partitions when they are collapsed, said supporting member including a flange lying substantially flat against said second partition and a bearing surface on said transverse partition member tending to hold said flange substantially against said second partition. 105
14. A partition member for a partition comprising a generally V-shaped article supporting member connected to one partition and extending in a general direction toward a second partition and arranged to fold up between said partitions when they are collapsed, said supporting member including a flange lying substantially flat against said second partition and a slot in said flange, and a lug on said partition member engaging said slot for supporting said flange while permitting said flange to move longitudinally relative to said second partition when the partitions are collapsed or expanded. 110
15. A partition member for a partition comprising a generally V-shaped article supporting member connected to one partition and extending in a general direction toward a second partition and arranged to fold up between said partitions when they are collapsed, said supporting member including a flange lying substantially flat against said second partition and a bearing surface on said transverse partition member tending to hold said flange substantially against said second partition. 115
16. A partition member for a partition comprising a generally V-shaped article supporting member connected to one partition and extending in a general direction toward a second partition and arranged to fold up between said partitions when they are collapsed, said supporting member including a flange lying substantially flat against said second partition and a slot in said flange, and a lug on said partition member engaging said slot for supporting said flange while permitting said flange to move longitudinally relative to said second partition when the partitions are collapsed or expanded. 120
17. A partition member for a partition comprising a generally V-shaped article supporting member connected to one partition and extending in a general direction toward a second partition and arranged to fold up between said partitions when they are collapsed, said supporting member including a flange lying substantially flat against said second partition and a bearing surface on said transverse partition member tending to hold said flange substantially against said second partition. 125
18. A partition member for a partition comprising a generally V-shaped article supporting member connected to one partition and extending in a general direction toward a second partition and arranged to fold up between said partitions when they are collapsed, said supporting member including a flange lying substantially flat against said second partition and a slot in said flange, and a lug on said partition member engaging said slot for supporting said flange while permitting said flange to move longitudinally relative to said second partition when the partitions are collapsed or expanded. 130
